UNITED STATES PATENT OFFICE

JOHN KARMAZIN, OF DETROIT, MICHIGAN

APPARATUS FOR FORMING RADIATORS

Application filed October 12, 1927. Serial No. 225,703.

This invention relates to improvements in methods for assembling sheet metal radiators and particularly relates to the method and means for assembling the fin and tube elements of the radiator as shown in my copending application Serial No. 88,738, filed Feb. 17, 1926.

In this prior application I have described a process for manufacturing and assembling radiator cores of the fin and tube type each of said radiator cores comprising a stack of superposed fin elements having integral tapered tubular projections, the projections of one element being adapted to telescope within the projections of the adjacent element whereby continuous water conduits are formed from end to end of the core.

It is one of the objects of this invention to provide an improved method and means for assembling the radiator cores of the formation as above described after the core elements leave the dies of the forming machine, by means of a downwardly and outwardly projecting chute and a horizontal compacting table.

It is another object of this invention to provide a simplified arrangement of machines for the purpose of conveying the formed fin and tube elements to the stacking machine in order that the process may be continuous and more rapid than the heretofore produced machines.

It is a still further object of this invention to provide a machine for manufacturing radiators in which a strip of sheet metal is progressively deformed to form a fin and tube element and which is suitably guided from the die to a horizontal stacking machine in order that the plurality of elements forming the radiator core may be under the operator's observation during the compacting action, thereby permitting the ready removal of any damaged element and its replacement before the final completion of the core.

It is a further object of this invention to provide a fin chute which receives the cut strip core elements in a vertical position from a die and by suitable means delivers a plurality thereof in partially aligned and com-

pacted arrangement to a final horizontal compacting table at which they are more desirably completed inasmuch as replacement may be made with the least effort, without interfering with the operation of the die machinery.

Further objects and advantages of the invention will appear from the following detailed disclosure thereof which in conjunction with the attached drawings illustrates a preferred form of embodiment and in which,

Figure 1 is an end elevation of the device from the rear diagrammatically showing the location of the die.

Figure 2 is a side elevation taken at right angles to Figure 1 and in which certain parts are in vertical section.

Figure 3 is a plan view of the cutter, chute, and compacting table.

The die 10 diagrammatically shown in Figure 1 is adapted to consecutively and progressively punch and draw a strip of sheet metal to form a fin and tube element such as is shown in my prior Patents No. 1,527,736, patented Feb. 24, 1925, and No. 1,591,322, patented July 6, 1926.

This strip or fin and tube element is punched on a continuous strip 12 which is diagrammatically shown to pass through the machine in the direction of the arrow in Figure 1.

From the die 10 the strip 12 passes through the feed rolls 14 and these rollers are formed to aid in this delivery as well as to support the strip on one side of the shear blades 16. The shear blades 16 cut the strip to the proper length which may be regulated to suit the size of the radiator core to be formed. The strip 17 after being cut projects beyond the cutters over the top of the chute 18 where it will be forced downward to the stacking table 20. In order that the cutters will operate at a proper point in the movement of the strip, a shaft 22 in positive connection with the die operating shaft (not shown), is provided with a pair of cams 23 and 24, see Figure 2. The cam 24 operates with the cam follower 25 which is directly connected to the shear blades 16. In other words, at each

complete revolution of the shaft 22 the shear blades 16 will be operated once by the rotation of the cam 24 and this rotation will be of the proper amount to correspond with the lineal discharge of the strip from the die. If longer fin and tube elements are desired to be produced, the relative rate of rotation of the shaft 22 may be regulated by suitable gearing in the positive driving connection from the main die drive shaft.

The other cam 23, also directly attached to the shaft 22, operates through the roller follower 27 to periodically move a pair of fingers 28. These fingers 28 project upwardly and outwardly and when in their uppermost position permit a fin and tube element to be placed in the upper end 18^a of the chute 18. After the core element 17 has been placed in position and sheared by the blades 16, further rotation of the shaft 22 forces the fingers 28 downwardly and, coming in contact with the element 17, they will displace the strip through the chute. Slots 19 in the upper part 18^a of the chute 18 permit free operation of these fingers 28.

It will thus be seen that the operation of the machine is continuous and involves the continuous roller 14 which automatically draws the formed material or metal strip therethrough discharging it to the chute in which the continuously operating fingers 28 will discharge it to the stacking table 20. The elements 17 all being cut to the proper length and being partially compacted in the chute and forced therefrom at the bottom 18^b, will then be moved from the end of the chute and finally compacted in full observation of the operator.

The bottom of the chute is provided with an extended table on which is a limit block 30 which is immovable. A lateral extension of the bottom of the chute is provided by the surface 32 on a level with the horizontal portion of the chute and on which a suitable number of core elements will be drawn from the chute to be further aligned if necessary, and compacted. The table top 32 is provided with a non-movable vertical face 33 and a longitudinally movable vertical face 34 in direct contact with a screw and wheel 36 operating through a nut block 37. A retaining plate 38 suitably locked in the movable face 34 by the pivoted plates 34^a, is pivoted to the table at 39. This retaining plate 38 secures the fin and tube elements from upward movement when the wheel and screw 36 are rotated to compact the elements forming the radiator core. A spring 40 aids in raising the arm 38 which will be released and raised when the core 41 comprised of a plurality of these individual fin and tube elements 17 is finally completed and compacted.

The operation of the device will thus be seen to include the proper manipulation of the die and the cooperation of the shear

blades which automatically cut the elements to the proper length and drop them in the chute. The fingers 28 then force the cut elements down the chute from which they are removed and placed on the compacting table at which time the operator, after locking the plate 38 on top of the core will then rotate the wheel and screw 36 until completed. At that time the wheel and screw will be released, the plate 38 raised and the core removed.

The operation is very rapid with the minimum of manual effort and permits the operator to notice the proper alignment of the projections on the fin and tube elements while noting that they are properly forced together permitting inspection as well as ease in fabrication. If any element should be damaged, its removal and replacement would be extremely easy on the horizontal table.

The chute 18 is adapted to be expanded or contracted either in width or in thickness in order that various sized elements may be provided. The adjustments 42 permit an adjustment in thickness and the adjustments 42 will be provided for the proper lengths of strip formed. As before mentioned, the strip itself may be changed in length by the proper change of strip feed ratio between the shaft 22 operating the cutter and the shaft operating the dies and the width of the strip may be varied by changing the dies. The wheel and screw 36 is also adapted to compact various lengths of core and will thus permit a variety of cores to be made on one machine.

From the foregoing disclosure it is obvious that I have produced a highly efficient machine for the particular purpose for which designed and which is an improvement on my prior application. The resistance furnished in the vertical chute and the horizontal travel from the end of the chute on the individual elements 17 is such that they will more readily align themselves and will thus aid in the speed at which the machine may operate. It is also unnecessary to stop the machine to remove the core elements after being compacted. By providing a machine that is readily adjustable, considerable economy may be effected as many sized cores are used in the automotive and analogous industries. The method of inspection provided by manual operation of the compacting machine is also important as it is highly essential that each of the multitude of individual projections on the tube elements cooperate with the adjacent one in order that a tight joint is made thereby and this may be assured by inspection on the horizontal compacting table rather than after the core was completed as formerly.

While I have shown a preferred form of embodiment of this invention, I am aware that modifications thereof may be made and I therefore desire protection on the herein

disclosed device and such modifications that fairly come within that disclosure and as more definitely brought out in the claims appended hereto.

I claim:

5. 1. In combination with a sheet metal forming machine of the character described, adapted for forming tubular projections on a strip of sheet material, means for assembling successive sections of said material with the tubular projections thereof in engaging relation, said means consisting of a downwardly and outwardly projecting chute through which the sections are forced with the tubular projections in horizontal alignment, means for forcing the sections through said chute and means at the bottom of the chute for supporting the sections for visual inspection and subsequent compacting.
10. 2. In combination with a sheet metal forming machine of the character described, adapted for forming tubular projections on a strip of sheet material, means for cutting said strip into elements, means for superposing said elements with the projections thereof in engaging relation, and means for horizontally compacting said elements in view of the operator.
15. 3. In combination with a radiator forming machine of the character described, adapted for forming tubular projections on a strip of sheet material, the walls of said projections being of substantially the same thickness as the sheet, and means for assembling the strip thus formed into a radiator, said means comprising a downwardly and outwardly projecting chute for preliminary alignment and a horizontal compacting table adjacent said chute for completing said core with said tubular projections in horizontal telescoped alignment.
20. 4. In combination with a radiator making machine, adapted for forming a strip of radiator element forming material from a strip of sheet material, and a device for cutting the strip thus formed into elements of uniform length, a stacking device adapted to superpose a predetermined number of said elements, said stacking device comprising a chute and fingers to force said elements vertically downward and horizontally outward from said chute.
25. 5. In combination with a radiator forming machine, adapted to form a plurality of rows of integral tubular projections from a flat sheet of metal, means to cut the formed sheet into elements of uniform size, means to stack the elements in superposed relation with the projections of one element in registry with the projections of the preceding element, comprising means for pressing one element against the other, and means to deliver said elements on a horizontal table, and means for compacting the stack of elements, said compacting means comprising a horizontally op-

erated block and a retaining plate above said elements to prevent displacement during compacting.

6. A cutting and stacking device of the class described adapted to receive a continuous strip of metal having a plurality of projections thereon, comprising cutting mechanism, a chute adjacent said cutting mechanism, said chute adapted to partially telescope adjoining strips, and means to complete the telescopic relation between adjacent strips.

7. A cutting and stacking machine of the class described adapted to receive a continuous strip of metal having a plurality of integral tapered projections thereon, comprising a cutting mechanism to cut the strip into elements of a predetermined size, a chute adjacent said cutting mechanism to receive said elements, said chute projecting downwardly and outwardly and adapted to partially compact said elements, and a horizontal table adjacent the end of said chute to complete the telescopic engagement of the elements.

8. A stacking device of the class described adapted to successively receive a plurality of sheet metal strips having a plurality of tubular projections thereon, comprising a downwardly and outwardly projecting chute, said chute adapted to partially telescope the tubular projections of adjoining strips, and means to complete the telescopic relation between adjacent strips.

9. A stacking machine of the class described adapted to receive a plurality of radiator core elements having a plurality of integral tapered projections thereon comprising a vertical chute having a horizontal outlet, said chute adapted to partially telescope the tapered projections of adjoining core elements, and a horizontal table adjacent the end of said chute provided with means to complete the telescopic engagement of the elements in horizontal position.

In testimony whereof I have affixed my signature to this specification.

JOHN KARMAZIN.
